UNITED STATES PATENT OFFICE

MARTIN BAUER, OF LAKESIDE, CLEVELAND, OHIO

LADDER

Application filed November 6, 1929. Serial No. 405,195.

My invention relates to improvements in ladders and while capable of applications to ladders generally has particular reference to the elongated type of ladder which is employed as an element of scaffolding by painters and other outside workmen.

It is a well known fact that after a certain period of use the rungs have a tendency to work loose in the holes or sockets in the side members. Thus, especially in a long ladder, the same has a tendency to sway or rock sideways,—which condition frequently results in a workman losing his footing on a scaffold board, which is supported by the ladder. To overcome the tendency of the rungs to work loose it has been the practice to wedge the rungs very tightly into the side members. However, this results in the side members splitting either during the operation of inserting the rung end therein, or as a result of a climatic or atmospheric condition after the ladder has gone into use.

It is, therefore, the primary object of my invention to provide means which will not only prevent the rung from working loose in the socket or hole in the side member of the ladder, but which will efficiently prevent splitting of the side members at any time.

A further object of the invention is to provide in a ladder,—or rather in the rung and side member connection,—novel means which will expose certain surfaces of the rung and its side member socket to air so as to permit the same to dry out quickly and to allow room for expansion from moisture or other causes, if need be.

The invention further contemplates a novel rung and side member connection for ladders which will be very simple in construction, inexpensive to manufacture, easily installed, and highly efficient in practical use.

The invention also contemplates certain novel features of construction, combination and arrangement of the various parts and various modes of operation, all of which will be readily understood and appreciated by those skilled in the art upon reference to the accompanying drawing in connection with the detailed description appearing herein-after.

While the drawing illustrates what is now regarded as a preferred mechanical expression of the invention, yet it will be understood that the device herein illustrated is merely to be taken as an example,—and in nowise limitative. It is obvious that the claims comprehend various alternative constructions for carrying out the objects referred to hereinabove.

In the drawing,

Figure 1 is an elevational view illustrating a portion of a ladder constructed in accordance with my invention;

Figure 2 is a side elevation of the ladder;

Figure 3 is an enlarged sectional view taken on the line 3—3 of Figure 1;

Figure 4 is a cross-sectional view of the socketed rung end and fitting elements taken on line 4—4 of Figure 1;

Figure 5 is a sectional view taken on the line 5—5 of Figure 1;

Figure 6 is a sectional view taken at right angles to the line of Figure 5, and

Figure 7 is a detail perspective view of one of the fitting members.

Referring specifically to the drawing, wherein the same reference characters have been used to designate the same parts in all views, numeral 1 denotes the side members or sills of the ladder,—the same having the holes or sockets 2 for receiving the reduced rounded ends 3^a of the rungs 3 which, as usual, connect or tie together, in spaced relationship, the side members 1.

Manifestly, if the ends 3^a of the rungs are made of substantially the same size as the socket holes 2 and are driven thereinto, the side members are very apt to split along the grain due to the lateral pressure of the ends 3^a when being driven in place. Of course, no damage can come from pressure exerted in the direction of the grain of the side members 1.

In carrying out my invention, the ends 3^a of the rungs are preferably made so as to have a rather loose fit in the holes 2, although both the rung ends 3^a and the holes 2 are preferably true circles. At the inner surface of each side member 1, I provide the rung confining members 5, which have plate-like ex-

tensions 5^a of arcual cross sections, which are inserted into the holes 2 and disposed diametrically opposite one another against the grain. In other words, one of the arcual plate extensions 5^a will be at the top of the hole and the other directly opposite at the bottom of the hole. Thus, the holes 2 will be reduced in diameter in the direction of the length of the side members 1, but not in the direction of the width of said side members. In other words, the holes 2 are of unreduced dimension transversely of the members 1. Thus, when the reduced end 3^a of the rung member 3 is forced into place there will be a wedging pressure only in the direction of the length of the side member 1 and it will be impossible to split the member because there is no wedging pressure exerted laterally, or "with" the grain, so to speak.

20 Of course, the arcuate extensions 5^a of the members 5 will occupy only about 90° of the diameter of holes 2.

It will be clearly seen from the drawing that the members 5 have an arcual body 5^b disposed against the inner surface of the side members 1 about the holes 2 and slightly outwardly of the marginal or rim of said holes. The body portions 5^b of the members 5 have the appearance of segments or portions of a socket, and in fact the two members or body portions 5^b when arranged in position, as shown, do cooperate to provide a socket for receiving the rung portion adjacent the reduced end 3^a. The portions 5^b of the members 5 exert a binding and supporting pressure against the unreduced portion of the rung 3 adjacent its socketed end.

Each of the members 5 has its body portion 5^b provided with a supporting bracket plate 5^c, which is screwed or otherwise fastened as at 6 to the surface of the side member 1 of the ladder. The plate portions 5^c have the appearance of tongues, as shown.

The members 5 are preferably made of 45 steel, aluminum or similar material, although they may be made of other substance within the spirit and scope of the invention. As I have shown the devices 5 they are made in one integral part. The manufacture of the 50 devices 5 is a simple casting or stamping problem and they may be made in whatever way seems most expedient.

It will be clear from the drawing and description that after the rungs have been 55 socketed in the holes 2 and the securing elements 5, 5^a employed as aforesaid, a small space will be left, as indicated at 8, at opposite sides of the reduced rung end 3^a to allow same to expand and exposing the socket and 60 rung end 3^a to air so that the same will readily dry out. All weight and pressure transmitted from the rungs 3 to the side members 1 will be directly against the grain of the side members, thus, obviating any likelihood of splitting the same.

The flange-like edge 5^b of members 5 adjacent the inner face of the side member 1 normally bears against the unreduced portion of rung 3. However, when the reduced rung end 3^a has partially rotted out such flange part of 5^b will enter space between member 1 and the shoulder at inner end 3^a of the reduced rung portion to support rung and apprise the owner that repairs are necessary.

Having thus described my invention, what I claim as new and desire to secure by Letters Patent is:

1. In a ladder comprising side members having rung sockets therein, and rungs connecting said side members and entering said sockets; a pair of opposed arcual take-up plates within said sockets and engaging the walls thereof against the grain for reducing the diameter of said sockets in the direction of the length of said side members, the arc of each of said plates being less than one-half the circumference of said sockets whereby to leave a ventilation space at each side of the inserted rung end and to allow for spreading of the same, the sockets being slightly oversize with respect to the ends of said rungs and the space between said plate members being slightly less than the diameter of the rung ends whereby the same may be driven into said sockets between said plate members and the pressure incident to such driving being exerted against the grain whereby to obviate the possibility of splitting the side members and at the same time to provide a very tight fit of the rungs in the sockets.

2. In a ladder comprising side members having rung sockets therein, and rungs connecting said side members and entering said sockets; a pair of opposed arcual take-up plates within said sockets and engaging the walls thereof against the grain for reducing the diameter of said sockets in the direction of the length of said side members, the arc of each of said plates being less than one-half the circumference of said sockets whereby to leave a ventilation space at each side of the inserted rung end and to allow for spreading of the same, the sockets being slightly oversize with respect to the ends of said rungs and the space between said plate members being slightly less than the diameter of the rung ends whereby the same may be driven into said sockets between said plate members and the pressure incident to such driving being exerted against the grain whereby to obviate the possibility of splitting the side members and at the same time to provide a very tight fit of the rungs in the sockets.

3. In a ladder comprising side members having rung sockets therein, and rungs connecting said side members and entering said

5   sockets; a pair of opposed arcual take-up plates within said sockets and engaging the walls thereof against the grain for reducing the diameter of said sockets in the direction of the length of said side members, the arc of each of said plates being less than one-half the circumference of said sockets whereby to leave a ventilation space at each side of the inserted rung end and to allow for spreading of the same, the sockets being slightly 10 oversize with respect to the ends of said rungs and the space between said plate members being slightly less than the diameter of the rung ends whereby the same may be driven 15 into said sockets between said plate members and the pressure incident to such driving being exerted against the grain whereby to obviate the possibility of splitting the side members and at the same time to provide a very 20 tight fit of the rungs in the sockets, each of said plate members having a segmental socket-like portion disposed at the inner surface of the side member adjacent the rung socket thereof, said segmental socket-like portions 25 disposed diametrically opposite one another and providing a socket-like support for the rung adjacent the end thereof.

4. In a ladder comprising side members having rung sockets therein, and rungs connecting said side members and entering said 30 sockets; a pair of opposed arcual take-up plates within said sockets and engaging the walls thereof against the grain for reducing the diameter of said sockets in the direction of the length of said side members, the arc of each of said plates being less than one-half the circumference of said sockets whereby to leave a ventilation space at each side of the inserted rung end and to allow for 35 spreading of the same, the sockets being slightly over-size with respect to the ends of said rungs and the space between said plate members being slightly less than the diameter of the rung ends whereby the same may be driven 40 into said sockets between said plate members and the pressure incident to such driving being exerted against the grain whereby to obviate the possibility of splitting the side members and at the same time to provide a very tight fit of the rungs in the 45 sockets, each of said plate members having a segmental socket-like portion disposed at the inner surface of the side member adjacent the rung socket thereof, said segmental socket-like portions disposed diametrically opposite one another and providing a socket-like support for the rung adjacent the end thereof, and an attaching portion carried by each of said segmental socket portions and adapted to be secured to the side 50 member of the ladder.

5. In a ladder comprising side members having sockets therein and rungs connecting said side members and entering said sockets, means for reducing the dimension of the

socket across the grain and in the direction of the length of the side member, the lateral dimension of said means being less than one-half of the circumference of said socket, whereby to leave a ventilation space at each side of the inserted rung end and to allow for spreading of the same. 70

6. In a ladder comprising side members having sockets therein and rungs connecting said side members and entering said sockets, a socket reduction element comprising a segmental plate adapted to be inserted into a socket and having an arc less than one-half the circumference of said socket, a segmental supporting portion disposed outwardly of said first mentioned portion and positionable adjacent the edge of the socket, and an attaching tongue carried by said last mentioned portion. 75 80

7. In a ladder comprising side members 85
having sockets therein and rungs connecting
said side members and entering said sockets,
segmental plates for reducing the dimension
of the socket in the direction of the length
of the side member and disposed against the
grain of the wood, said plates disposed dia-
metrically opposite one another, and the ar-
cual span of each plate being less than one-
half the circumference of the socket where-
by to leave lateral rung-spread-permitting
and ventilation spaces. 90 95

8. In a ladder comprising side members having sockets therein and rungs connecting said side members and entering said sockets, segmental plates for reducing the dimension of the socket in the direction of the length of the side member and disposed against the grain of the wood, the arc of each plate being less than one-half the circumference of said socket whereby to leave a rung-spread-
permitting and ventilation space at each side of the inserted rung. 100 105

9. In a ladder comprising side members having sockets therein and rungs connecting said side members and entering said sockets, a socket reduction element comprising a segmental plate adapted to be inserted into the socket, a segmental supporting portion disposed outwardly of said first mentioned portion and positionable adjacent the edge of the socket, said segmental supporting portion being of channel-like cross-section and having a flange lying against the adjacent surface of said side member whereby to engage the socketed end of the rung upon rotating out thereof, said plates having an arc less than one-half the circumference of said socket whereby to leave a rung-spread-permitting and ventilation space at each side of the inserted rung. 110 115 120 125

In testimony whereof I affix my signature.
MARTIN BAUER.
